DOOR LATCH MECHANISM

Raymond Heizmann, Shillington, Pa.

Application March 22, 1939, Serial No. 263,345

12 Claims. (Cl. 70—153)

This invention relates to door latch mechanism and it is concerned more particularly with latch mechanism of the type wherein the latch bolt is actuated by a spindle which passes through the door and which is fitted at opposite ends with manipulating grasp knobs.

In connection with latch mechanism of the type referred to, I aim to make it possible to set the latch bolt so that it cannot be operated by means of the outside knob, without precluding its operation at any time by means of the inside knob.

Another aim of my invention is to attain the above advantages in door latch mechanism which is reliable in operation; which embodies a minimum number of parts in its construction; which is easily assembled incident to installation on the door; and which, moreover, lends itself to ready manufacture at very small cost.

Other objects and attendant advantages will appear from the following description of the attached drawings, wherein Fig. I is a view in transverse vertical section of a door embodying my improved latch mechanism.

Fig. II is a view like Fig. I showing the mechanism in locked position.

Fig. III is a fragmentary view partly in elevation and partly in section taken as indicated by the arrows III—III in Fig. I.

Fig. IV is a detail sectional view taken as indicated by the arrows IV—IV in Fig. II.

Figs. V and VI are perspective views respectively of two parts which, in accordance with my invention, together constitute the bolt actuating spindle of the latch mechanism.

Figs. VII and VIII are perspective views of bushings respectively for the outside and inside door knobs of the latch mechanism; and,

Fig. IX is a fragmentary perspective view showing how the components of the spindle are interengaged with a bushing whereto the outside manipulating knob is secured.

With more detailed reference to the drawings, I comprehensively designates a standard form of latch bolt unit which is recessed into the swinging edge of the door 2, and which has a projecting beveled latch bolt 3 adapted to engage a keeper (not shown) on the door jamb. The illustrated latch unit 1 may be of any approved construction having a cylindric body 4 with a face plate 5 at one end thereof through which the securing screws 6 pass. The latch bolt 3 is operable against spring pressure in a well known way through suitable connections (not illus-

trated) within the cylindric body 4, by rotation of the hub indicated at 7.

Disposed at opposite sides of the door 2 in axial alignment with the hub 7 of the latch unit 1 and secured to the door by screws 8 and 9, are centrally-apertured circular escutcheons 10 and 11 respectively having outwardly-projecting bosses 12 and 13 with socket recesses 14 and 15. The means for actuating the latch bolt 3 includes outside and inside manipulating knobs 16 and 17 which are shown as being of hollow sheet metal construction with axial cylindric shanks 18 and 19 respectively. As shown, the shank 18 of the outside knob 16 fits into the socket recess 14 of the escutcheon 10, and secured within it by spot countersunk connections 20 is a bushing 21. Similarly secured within the shank 19 of the inside knob 17 by spot countersunk connections 22, is a bushing 23 which has a diametrically-reduced projecting portion 24 fitting into the socket recess 15 of the escutcheon 11. The knobs 16 and 17 are held in the assembly by a retaining element in the form of a flat bar 25 of oblong cross section which passes continuously through the door 2, the latch hub 7, the escutcheons 10 and 11, and the bushings 21 and 23, and which has lateral projections 26 and 27 at its opposite ends which overlap shoulders afforded within the knobs by the remote ends of said bushings. As shown in Fig. VII, the inner shoulder end of the bushing 21 for the outside knob 16 is formed with steps as at 28, 29, 30 and 31, which, by placement of said bushing in different circumferential positions for selective coaction with the projection 26 of the retaining bar 25, makes possible the adaptation of the latch mechanism to doors of different thicknesses. Also extending continuously through the door 2, the latch hub 7, the escutcheons 10 and 11 and the knob bushings 21 and 23 is an endwise slideable bar 32, which, like the retaining bar 25, is oblong in cross section, the cross sections of the two being so proportioned as to jointly fill the square opening 33 in the latch hub 7 and the square axial opening 34 of corresponding size in the bushing 21 of the outside knob 16. The bars 25 and 32 thus jointly constitute the latch operating spindle of the mechanism. The bore 35 of the bushing 23 of the inside knob 17, it will be noted from Fig. VIII is cylindric, and as shown in Fig. IV of a diameter to clear the two spindle components 25 and 32. At its inner end, the shiftable spindle component 32 is formed with a push button head 36 which normally projects outward 55

through and axial opening 37 in the inside knob 17, see Fig. I. The bar 32 moreover has a pair of spaced projecting lugs 38, 39 at one of its corner angles adjacent the button head 36. As shown, the lug 39 extends into a longitudinal groove 40 internally of the bushing 23 of the inside knob 17, said groove being relatively wide as shown in Fig. IV so as to permit a limited amount of turning movement of the knob in either direction on the spindle for a purpose presently explained. The lug 39 is adapted to enter a notch 41 in the inside escutcheon 11 when the spindle component 32 is pushed inward of the knob 17 to the position shown in Fig. II and thereby prevents operation of the latch bolt 3 by means of the outside knob 16. Lodged within the internal groove of the inside knob bushing 23 is a leaf spring 42 with spaced offsets 43 which are adapted to cooperate with the lug 38 to prevent accidental displacement of the bar 32 in either of its two positions respectively shown in Figs. I and II. The bar 32 is held against withdrawal through cooperation of a lug 44 on its head 36 with the inside of the outer wall 45 of the knob 17 after passage through a notch 50 in the latter. At its outer end, the bushing 23 of the inside knob 17 has a double faced beveled cam projection 46 (Figs. I and VIII) which is normally aligned for coaction with a reversely-configured cam recess 47 (Figs. I, II and V) in the inner end of the button head 36 on the bar 32; said notch being of greater width than the cam projection to permit slight independent relative rotation of the inside knob 17 as later on further explained.

The operation of my improved latch operating mechanism is as follows:

With the spindle component 32 positioned as shown in Fig. I, it is possible to operate the latch bolt 3 by means of either the outside or inside knob 16, 17, respectively, since the lug 39 on said component is at this time withdrawn from the notch 41 in the escutcheon 11. The mechanism may be locked against operation from the outside with the knob 16 by pushing upon the button head 36 of the bar 32 at the inside knob 17, with the result that the lug 39 on said bar is engaged in the notch 41 of the inside escutcheon 11 as shown in Fig. II. The door 2 however may be opened at any time from the inside by turning the knob 17. Upon initiation of the turning of the knob 17 in one direction or the other, the bar 32 will be shifted rightward in Fig. II as a result of coaction of the cam projection 46 with the cam depression 47, in the inner end of the button head 36, until said bar 32 reassumes the position shown in Fig. I with its lug 39 withdrawn from the notch 41 in the escutcheon 11. In this connection it is to be noted that the width of the groove 40 in the bushing 23 of the inside knob 17 is such as to allow the immediately foregoing action to take place before the side of the groove 40 engages the lug 39 to cause rotation of the spindle 32 as the knob 17 is turned further in the same direction to operate the latch bolt 3. In order that the bar 32 may be shifted back to its normal position from without the door, the knob 16 is provided with a slot 48 (Fig. I) for reception of a suitable key 49. Thus when the key 49 is inserted, its inner end encounters the bar 32 and pushes the latter rightward until the lug 39 is disengaged from the notch 41 of the escutcheon 11 as in Fig. I, so that the door can be opened by means of the outside knob 16.

In assembling my improved latch operating

mechanism, the latch bolt unit 1 is first mortised in the usual way into the swinging edge of the door 2. The bar 25 is next thrust into the knob 17 and its end projection 27 hooked over the inner end of the bushing 23, and the bar 32 thereupon inserted through the hole 37 in the knob 17 until its forward end is flush with the end of the knob shank 19. With this preparation, the escutcheon 11 is placed over the projecting end 24 of the bar 25 and the latter pushed through the opening 33 in the hub 7 until the escutcheon 11 rests against the door 2 and the knob 17 bears against said escutcheon. With the bar 25 still held tightly in place by the bar 32, the outside escutcheon 12 is run on and the knob 16 applied and its bushing 21 hooked by engagement of the lateral end projection 26 of the bar 25 over the proper one of the step shoulders 28-31 of said bushing. The bar 32 is next run home and locked into position by turning the inside knob 17 until the lug 44 has passed through the notch 50, whereupon the escutcheons 10 and 11 are finally secured in place by the screws 8 and 9.

Dismounting of the latch mechanism is effected simply by turning the knob 17 to register its slot 50 with the lug 44 of the button 36 and then withdrawing the latter and bar 32 whereupon the assembly will of itself fall apart in an obvious manner.

Having thus described my invention, I claim:

1. Door latch mechanism comprising a latch unit with a latch bolt operating hub; inside and outside door knobs; and a lengthwise split spindle of polygonal cross section fitting a correspondingly configured opening through the latch operating hub, said spindle being formed of two bar components one of which is non-shiftable, said non-shiftable component embodying integrally-formed means for interlocking the two knobs, and means associated with the other component when shifted endwise for locking or unlocking said knobs.

2. Door latch mechanism according to claim 1, wherein the spindle non-shiftable bar component knob-interlocking means consist of lateral projections from said component which engage over shoulders internally of the two knobs to hold said knobs in place.

3. Door latch mechanism according to claim 1, wherein the door knobs have spindle engaging bushings; and the spindle non-shiftable bar component has lateral retaining projections which overlap the inner ends of the knob bushings to hold the knobs in place.

4. Door latch mechanism according to claim 1, wherein the door knobs have spindle engaging bushings; the non-shiftable bar component of the spindle has lateral retaining projections which overlap the inner ends of the knob bushings to hold the knobs in place; and the inner end of one of the knob bushings has steps providing a number of shoulders which, upon placement of such bushing in different positions circumferentially of the spindle, enable application of the mechanism to doors of different thicknesses.

5. Door latching mechanism according to claim 1, wherein a member having a notch is fixed to the door, the shiftable bar component of the spindle extends through the inside knob and has a lateral lug, said lug, when the bar component is pushed inwards, engaging in the fixed member notch to dog the spindle and thereby prevent operation of the latch bolt by the outside knob.

6. Door latching mechanism according to claim 1, wherein an escutcheon through which the spindle passes is secured to the inner side of the

door, said escutcheon having a notch; the shiftable bar component extends through the inside knob and has a lateral lug, said lug, when the bar component is pushed inwards, engaging the 5 escutcheon notch to dog the spindle and thereby prevent operation of the latch bolt by the outside knob.

7. Door latching mechanism according to claim 1, wherein a member having a notch is fixed to the 10 inside of the door, the shiftable bar component of the spindle extends through the inside knob and has a lateral lug, said lug, when the shiftable bar component is pushed inward of said inside knob, engaging in the fixed member notch to 15 dog the spindle and thereby prevent operation of the latch bolt by means of the outside knob; and the outside knob is provided with a slot for insertion of a key to release the spindle shiftable component for operation of the latch bolt by 20 means of the outside knob.

8. Door latch mechanism according to claim 1, wherein a member having a notch is fixed to the door, the shiftable bar component of the spindle extends through the inside knob and has a lateral lug, said lug when the bar is pushed inward of said inside knob, engaging the notch in the fixed member aforesaid to dog the spindle and thereby prevent operation of the latch bolt by the outside knob; and the inside knob includes means 25 for coaction with the shiftable bar component whereby, upon initiation of turning movement thereof, said component is unlocked to permit operation of the latch bolt by continued turning of the inside knob.

35 9. Door latch mechanism according to claim 1, wherein the outside knob is fixed upon the non-shiftable spindle component; a member having a notch is fixed to the inside of the door; the shiftable spindle component extends through the inside 40 knob and has a lateral lug which, when said shiftable component is pushed inward of the inside knob, engages the notch in the fixed member aforesaid to dog the spindle and thereby prevent operation of the latch bolt by said inside knob, 45 said notch being of a width to permit slight independent rotative movement of the inside knob on the spindle; and opposing cam surfaces, respectively on the shiftable spindle component and on the inside knob, cooperating 50 during the slight independent rotative movement of said inside knob to automatically withdraw the shiftable spindle component so that the latch bolt may be operated by continued turning of said inside knob.

55 10. Door latch mechanism according to claim 1, wherein the outside knob is fixed upon the non-shiftable spindle component; a member having a notch is fixed to the inside of the door; the shiftable spindle component extends through the inside 60 knob and has a lateral lug which, when said shiftable component is pushed inward of the inside knob, engages the notch in the fixed member on the door to dog the spindle and thereby prevent operation of the latch bolt by said inside knob, and said notch is of a width to permit limited rotative movement of the inside knob in either direction on the spindle; and opposing cam

surfaces, respectively on the shiftable spindle component and the inside knob, cooperate during the limited rotative movement of the inside knob in either direction, to automatically withdraw the shiftable spindle component so that the latch may 5 be operated by continued turning of said inside knob in the same direction.

11. Door latch mechanism according to claim 1, wherein the outside knob is fixed upon the non-shiftable spindle component; a member having a notch is fixed to the inside of the door; the shiftable spindle component extends through the inside knob and has a lateral lug which, when said shiftable component is pushed inward of the inside knob, engages the notch in the fixed member 10 on the door to dog the spindle and thereby prevent operation of the latch bolt by the outside knob; the inside knob having an axial bushing with an interior groove; the shiftable spindle component having a second lug which projects 15 into the bushing groove, said groove being somewhat wider than the last mentioned lug to permit slight rotative movement of the inside knob in either direction independently of the spindle; the bushing aforesaid having a double faced cam 20 projection, and the shiftable component having a shoulder with a reversely configured cam recess; and said cam projection and recess cooperating during the slight rotative movement of the inside knob in one direction or the other to effect automatic withdrawal of the shiftable spindle component 25 so that the latch bolt may be operated by continued turning of the inside knob in the same direction.

12. Door latch mechanism according to claim 1, 35 wherein the outside knob is fixed upon the non-shiftable spindle component; a member having a notch is fixed to the inside of the door; the shiftable spindle component extends through the inside knob and has a lateral lug which, when said shiftable component is pushed inward of the inside knob, engages the notch in the fixed member on the door to dog the spindle and thereby prevent operation of the latch bolt by the outside knob; the inside knob having an axial bushing 40 with an interior longitudinal groove; the shiftable spindle component having a second lug which projects into the bushing groove, said groove being somewhat wider than the last mentioned lug to permit slight rotative movement of the inside knob in either direction independently of the spindle; the bushing aforesaid having a double faced cam 45 projection, and the shiftable component having a shoulder with a reversely configured cam recess; said cam projection and recess jointly 50 cooperate during the slight rotative movement of the inside knob in one direction or the other to effect automatic withdrawal of the shiftable spindle component so that the latch bolt may be operated by continued turning of the inside knob in the same direction; and a yielding member 55 with spaced notches within the bushing groove to coat with the last mentioned lug to prevent accidental displacement of the shiftable spindle component in either of its two positions.

RAYMOND HEIZMANN.
